D20138

UNITED STATES PATENT OFFICE

WILLIAM H. FREYFOGLE, OF HAVERSTRAW, ASSIGNOR TO THE HOPKINS & DICKINSON MANUFACTURING COMPANY, OF BROOKLYN, NEW YORK.

DESIGN FOR AN ESCUTCHEON, &c.

SPECIFICATION forming part of Design No. 20,138, dated September 9, 1890.

Application filed July 30, 1890. Serial No. 360,425. Term of patent 7 years.

To all whom it may concern:

Be it known that I, WILLIAM H. FREYFOGLE, a citizen of the United States, residing at Haverstraw, in the county of Rockland and State of New York, have invented and produced a new and original Design for a Combined Escutcheon, Rose, and Knob; and I do hereby declare the following to be a full, clear, and exact description of the invention, such as will enable others skilled in the art to which it appertains to make and use the same, reference being had to the accompanying photographic view, and to letters of reference marked thereon, which form a part of this specification.

Referring to said photograph, which represents a view in perspective of an escutcheon, rose, and knob showing my design, and is deemed sufficient to fully illustrate the same,

20 A indicates the escutcheon, and B the knob.

The leading features of my design consist in the peculiar ornamentation of the surface of the several parts, as herein set forth, and embodied in the claim.

25 In the view, a indicates a raised scalloped border surrounding the edge of the escutcheon.

b indicates a raised oblong bar extending

through the center from the rose toward the lower end of the escutcheon and branching 30 off at each side both top and bottom, and at the lower extremities thereof into a raised vine-like ornamentation c, which extends to the lower end of the escutcheon. The upper extremity of said bar breaks into a raised 35 ring d, which encircles the rose, and above the latter and extending to the upper end of the escutcheon is also a raised vine-like ornamentation e, similar to that at the lower end. The sunken surfaces of the escutcheon-plate 40 and the rose are embossed to represent spider-webs f. The knob is circular in form and plane, except the front, which has a sunken embossed web-like surface g and a raised vine-like ornamentation h thereon, all as 45 shown.

What I claim is—

The design for an escutcheon, rose, and knob herein shown and described.

In testimony that I claim the foregoing I 50 have hereunto set my hand this 25th day of July, 1890.

WILLIAM H. FREYFOGLE.
